Primary Examiner — Phillip S Hyder(74) *Attorney, Agent, or Firm* — McDonnell Boehnen Hulbert & Berghoff LLP(57) **CLAIM**

The ornamental design for a wire stripper, as shown and described.

DESCRIPTION

FIG. 1 is a perspective view of a wire stripper according to my new design;

FIG. 2 is a front side elevation view thereof;

FIG. 3 is a rear side elevation view thereof;

FIG. 4 is a bottom plan view thereof;

FIG. 5 is a top plan view thereof;

FIG. 6 is a right side elevation view thereof; and,

FIG. 7 is a left side elevation view thereof.

The broken lines depict portions of the wire stripper in which the design is embodied that are not considered part of the claimed design.

1 Claim, 3 Drawing Sheets(56)
